UNITED STATES PATENT OFFICE.

RUDOLPH A. WITTEMANN, OF NEW YORK, N. Y.

SULPHURING-TUBE.

SPECIFICATION forming part of Letters Patent No. 335,050, dated January 26, 1886.

Application filed October 13, 1885. Serial No. 179,825. (No model.)

To all whom it may concern:

Be it known that I, RUDOLPH A. WITTEMANN, of the city, county, and State of New York, have invented certain new and useful 5 Improvements in Sulphuring-Tubes, of which the following is a specification.

This invention relates to an improved sulphuring-tube or tube for burning sulphur in wine and other barrels, by which the drip 10 from the sulphuring-strip is prevented from dropping into the barrel; and the invention consists of a sulphuring-tube the body of which is suspended in the barrel, and provided with a detachable bottom and an enlarged head 15 having a hinged bail. On the head rests a cap having a suspension-wire, to which the sulphuring-strip is applied.

In the accompanying drawings, Figure 1 represents a vertical central section of my improved sulphuring-tube. Fig. 2 is a top view, 20 and Fig. 3 a horizontal section on line $x-x$, Fig. 1.

Similar letters of reference indicate corresponding parts.

Referring to the drawings, A represents the 25 perforated tubular body of my improved sulphuring-tube, which body is made of such a size that it can be readily inserted through the faucet-hole or bung-hole of a wine or other 30 barrel. To the tapering lower end of the tube A is tightly fitted a detachable bottom cap, A', which receives the drip of the sulphuring-strip and prevents it from dropping into the barrel. The upper end of the tube A is attached to a ring-shaped head, B, which is bent 35 up at diametrically-opposite sides, so as to form ears b b, for attaching a bail, C, by means of which the tube can be readily handled for removing it from or inserting it into the barrel. The upper end of the tube A is closed 40 by a flanged disk, D, to which is attached a suspension-wire, E, by an enlarged eye, a. To the lower hook-shaped end of the suspension-wire E is applied the sulphuring-strip F. The 45 same is lighted at the lower end before it is in-

serted into the tube A, and then lowered slowly into the same until the disk D closes the upper end of the tube. The head B closes the faucet or bung-hole, so that the fumes of the burning sulphur are retained at the interior of the barrel. The drip of the burning strip F and the burned parts of the same are collected by the bottom cap, to be removed with the tube, and are prevented from dropping into the barrel.

My improved sulphuring-tube facilitates the burning of sulphur in wine and other barrels and casks, and forms a cheap and convenient device for accomplishing this operation in a clean manner.

I am aware that sulphuring-tubes that are supported in the bung-hole of a barrel so as to catch the drip of the sulphuring-strip and diffuse the fumes in the barrel have been used heretofore, and I do not claim the same, broadly.

Having thus described my invention, I claim as new and desire to secure by Letters Patent—

1. A sulphuring-tube consisting of a perforated tubular body having a detachable bottom cap, an enlarged head attached to the upper end of the tube, a disk resting on said head, and a suspension-wire supported by said disk and adapted to support the sulphuring-strip, substantially as set forth.

2. A sulphuring-tube consisting of a tubular perforated body having a detachable bottom cap, an enlarged head attached to the upper end of the body, a bail applied to ears of the head, a disk resting on the head, and a suspension-wire attached to the cap and adapted to support the sulphuring-strip, substantially as set forth.

In testimony that I claim the foregoing as my invention I have signed my name in presence of two subscribing witnesses.

RUDOLPH A. WITTEMANN.
